UNITED STATES PATENT OFFICE.

WILLIAM THORNE SUMMERS, OF COLUMBUS, OHIO.

DESIGN FOR A HEEL.

SPECIFICATION forming part of Design No. 29,452, dated October 4, 1898.

Application filed August 24, 1898. Serial No. 689,435. Term of patent 7 years.

To all whom it may concern:

Be it known that I, WILLIAM THORNE SUMMERS, of Columbus, in the county of Franklin and State of Ohio, have invented and produced a new and original Design for Heels for Boots and Shoes, whereof the following is a specification, reference being had to the accompanying drawings, forming a part thereof.

In said drawings, Figure 1 is a plan view of the top lift of a heel, showing my new design. Figs. 2 and 3 are respectively a side edge view and a forward edge view of the same.

As shown in the drawings, the leading or material feature of my design consists of the

three projections extending perpendicularly from the surface of the top lift or wearing-face of the heel. These projections are of flat cylindrical form and located according to the triangular arrangement shown. 20

Having described my invention, what I claim as new, and desire to secure by Letters Patent, is—

The design for a heel substantially as herein shown and described.

WILLIAM THORNE SUMMERS.
